UNITED STATES PATENT OFFICE

2,547,478

TARGET FOR FIREARM PRACTICE

Philip S. Lieberman, Clarence, N. Y.

Application July 7, 1948, Serial No. 37,368

7 Claims. (Cl. 273—102.1)

1

This invention relates to targets for use in marksmanship and particularly to an automatically reset target.

According to the present invention a target device is provided which is simple and rugged in construction and which is so arranged that the target element proper is a plate-like element which alternately presents its opposite flat surfaces as target objectives. Such opposite surfaces are presented at different locations relative to the general support of the target to clearly indicate a hit, the plate-like element being arranged to automatically reverse and present its opposite surface upon being struck by a bullet or other projectile.

Means are also provided, in the target of the present invention, for varying the force required to produce reversal of the target element, so that the device may readily be adjusted for use with bullets or other projectiles of varying fire power. The adjusting means may be set to reverse in any selected impact range, whereby proper operation may be provided under any desired conditions, the impact on the target varying not only with the size and type of projectile but also with the distance at which shooting is taking place.

An important feature of the self-setting characteristics of the device of the present invention resides in its contribution to greater safety. Many shooting accidents occur as a result of persons walking into a firing range to set up or reset targets or other shooting objectives. In using the device of the present invention no such attention is required after the target is initially placed in the desired position.

Various other objects and advantages of the target of the present invention will occur to those skilled in the art from a consideration of the following specification and the accompanying drawing. It is to be understood, however, that various mechanical modifications may be made in the device disclosed herein by way of example without departing from the spirit of the invention, which is not limited excepting as defined in the appended claims.

In the drawing:

Fig. 1 is a front elevational view of one form of the target device of the present invention with a portion thereof broken away for added clarity of illustration; and

Fig. 2 is a top plan view thereof.

In the several figures of the drawing like characters of reference denote like parts and the numeral 10 designates a plate or body element which comprises the main support of the device. A pair of legs 11 and 12 are rigidly secured to the side marginal edges of plate 10 at their upper ends, as by welding or the like, and extend downwardly. The legs 11 and 12 may be pointed at their lower ends to facilitate sticking them into

2

the ground or they may be employed in another desired manner to support the plate element 10 in an exposed position. In place of the foregoing supporting assemblage, the plate 10 and legs 11 and 12 may be fabricated from a single sheet metal blank, as by stamping or the like.

Plate element 10 has fixed to its rear face, as by welding or the like upper and lower rearwardly extending bearing plates 14 and 15, the upper bearing plate 15 being of greater rearward extent than the lower for reasons which will presently appear.

The target itself comprises a plate 16 which is shown in the present instance to be square but which might be circular or of any other desired configuration. Target 16 may be integral with a supporting arm portion 17 or may be fixed thereto by welding, as shown, and the latter is in turn fixed adjacent to its inner end to a vertical pivot pin 18.

Pivot pin 18 has reduced upper and lower end portions which have bearing in the upper and lower bearing plates 14 and 15, respectively. The upper reduced portion of pivot pin 18 extends above bearing plate 14 and has fixed thereto, in any desired manner, a flat-sided cam element 20 having a nose portion 21.

At its rear portion upper bearing plate 14 has fixed to its upper surface, as by welding or the like, a vertical plate element 23 which serves as a mounting plate for resilient target-positioning means. A cam follower plate 24 has an aperture at its rear portion and the forward end normally bears against one or the other of the flat sides of cam element 20.

The plate element 23 is also apertured and a bolt 25 passes through plate element 23 and cam follower plate 24 and thence through a compression coil spring 26, being provided at its outer end with a suitable adjusting wing nut 27.

The rear edge of cam follower plate 24 bears against the rigid plate element 23 which provides a fulcrum for the cam follower plate. Its forward portion is thus urged horizontally toward and against cam element 20 and the resilient force which resists turning movement of cam element 20 is obviously determined by the force of spring 26 as adjusted by wing nut 27.

When the target 16 is in the left-hand position illustrated in Fig. 1, nose portion 21 of cam element 20 is directed rearwardly. When target 16 is struck by a bullet or other projectile, nose portion 21 of cam element 20 rides against follower plate 24 and rocks the latter about its rear fulcrum against the resistance of spring 26 until the cam passes over center, whereupon the spring acts against the cam to quickly complete a 180° arc of movement whereupon follower plate 24 bears resiliently but firmly against the

opposite flat side of cam element 20 with the nose portion 21 of the latter projecting forwardly.

The target 16 is thus positioned at the right-hand side of plate element 20 for further shooting and its change of position clearly marks the fact that a hit has been scored. The adjustment of spring 26 may be such that the impact of the projectile itself is sufficient to complete the 180° arc of movement, the spring serving merely a retaining function.

Proper adjustment of the force of spring 26 will assure against the target 16 moving 180° to the other side of plate element 19 and immediately rebounding to the first side from the force of a single "hit."

In one form the body plate element 16 and legs 11 and 12 may be painted a dark color with target 16 painted white or some other light color, but obviously the contrasting color arrangement may be varied to suit individual conditions or individual tastes. To facilitate assembly, upper bearing plate 14 has a U-shaped notch 36 for receiving the upper reduced portion of pivot pin 18, the latter being held assembled by the pressure of follower plate 24.

What is claimed is:

1. In a target, a front stationary plate and means for supporting the same, a vertical pivot disposed centrally behind said plate, an arm supported for swinging movement by said pivot and having a flat target plate at its outer end, said arm and target plate normally extending generally parallel to the front plate with the target plate exposed at one side of the front plate, said arm and target plate being adapted to swing rearwardly thence forwardly to an opposite position also generally parallel to the front plate with the target plate exposed at the opposite side of the front plate, over-center resilient means urging the target plate to either of its limit positions at opposite sides of the front plate, and manual means for varying the stress of the resilient means.

2. In a target, a front stationary plate and means for supporting the same, a vertical pivot pin disposed centrally behind said plate and pivoted thereto, an arm fixed to said pivot pin for swinging movement therewith and having a flat target plate at its outer end, said arm and target plate normally extending generally parallel to the front plate with the target plate exposed at one side of the front plate, said arm and target plate being adapted to swing rearwardly thence forwardly to an opposite position also generally parallel to the front plate with the target plate exposed at the opposite side of the front plate, an elongate cam on said pivot pin, and resilient means adapted to bear alternately against opposite sides of said cam to yieldably retain the target plate in either of its limit positions at opposite sides of the front plate.

3. In a target, a front stationary plate and means for supporting the same, a vertical pivot pin disposed centrally behind said plate and pivoted thereto, an arm fixed to said pivot pin for swinging movement therewith and having a flat target plate at its outer end, said arm and target plate normally extending generally parallel to the front plate with the target plate exposed at one side of the front plate, said arm and target plate being adapted to swing rearwardly thence forwardly to an opposite position also generally parallel to the front plate with the target plate

exposed at the opposite side of the front plate, an elongate cam on said pivot pin, resilient means adapted to bear alternately against opposite sides of said cam to yieldably retain the target plate in either of its limit positions at opposite sides of the front plate, and manual means for readily varying the tension of said resilient means.

4. In a target, a front stationary plate and means for supporting the same, a vertical pivot disposed centrally behind said plate, an arm supported for swinging movement by said pivot and having a flat target plate at its outer end, said arm and target plate normally extending generally parallel to the front plate with the target plate exposed at one side of the front plate, said arm and target plate being adapted to swing rearwardly thence forwardly to an opposite position also generally parallel to the front plate with the target plate exposed at the opposite side of the front plate, and over-center resilient means urging the target plate to either of its limit positions at opposite sides of the front plate.

5. In a target, a front stationary plate and means for supporting the same, a vertical pivot disposed centrally behind said plate, an arm supported for swinging movement by said pivot and having a flat target plate at its outer end, said arm and target plate normally extending generally parallel to the front plate with the target plate exposed at one side of the front plate, said arm and target plate being adapted to swing rearwardly thence forwardly to an opposite position also generally parallel to the front plate with the target plate exposed at the opposite side of the front plate, and means for yieldably retaining the target plate in either of its limit positions at opposite sides of the front plate.

6. In a target, a support, a reversible flat target plate having its opposite faces alternately disposable at opposite sides of said support, means at the rear of said support engageable with the target plate to mount the latter for swinging movement through substantially 180° to present its opposite face at the opposite side of said support, and over-center spring means for resiliently urging the target plate to either of its limit positions at one side or the other of said support.

7. In a target, a support, a reversible flat target plate having its opposite faces alternately disposable at opposite sides of said support, means at the rear of said support engageable with the target plate to mount the latter for swinging movement through substantially 180° to present its opposite face at the opposite side of said support, over-center spring means for resiliently urging the target plate to either of its limit positions at one side or the other of said support, and manual means for readily varying the tension of said spring means.
